UNITED STATES PATENT OFFICE

EARL C. CHILDERS, OF KANSAS CITY, MISSOURI, ASSIGNOR TO JOHN K. THOMPSON, OF KANSAS CITY, MISSOURI

SHORE

Application filed February 4, 1929, Serial No. 337,360. Renewed January 18, 1932.

This invention relates to shores of that class involving the use of a base member and an adjustable member fitting in telescopic relation, and susceptible of being secured in a fixed relationship at any desired point of adjustment, and my object is to produce a shore of the general class identified, which is efficient in operation and of simple, strong, durable and inexpensive construction, a further object being to provide means for preventing accidental separation of the members. Another object is to provide automatic means to normally clamp the members in fixed relation and manually-operative means for intensifying such clamping action or for effecting or permitting relaxation of such clamping action.

With these objects in view the invention consists in certain novel and useful features of construction and combinations of parts as hereinafter described and claimed; and in order that it may be fully understood, reference is to be had to the accompanying drawing, in which:

25 Figure 1 is a fragmentary view partly in side elevation and partly in central vertical section of a shore embodying the invention, the members of the shore being shown in clamped or fixed relation.

30 Figure 2 is a view showing in section the part appearing in elevation in Figure 1, and in elevation the part appearing in section in Figure 1.

Figure 3 is a horizontal section taken on the line III—III of Figure 1.

Figure 4 is a top plan view of a fitting forming a part of the invention.

Referring to the drawing in detail, 1 indicates the base member of the shore, the same being preferably in the form of an upright pipe section and adapted to be equipped at its lower end with a conventional base, not shown, for resting upon the ground or any suitable support. The said member is grooved at its upper end to provide an upwardly-tapering wedge portion 2 and an overlying downwardly-facing stop shoulder 3.

The upper member 4 of the shore fits telescopically on the base member and is provided near its lower end with an offset cham-

ber 5 containing a locking pin 6 and a spring 7 for holding the locking pin against the base member and for projecting it yieldingly into the grooved upper end of said member when the upper member is adjusted upward to the limit of its movement. It will be noted that when the pin is engaging said groove any attempt to slide the upper member higher will be prevented by the engagement of the pin with the downwardly-facing stop shoulder 3, it being also noted that the upper member is not prevented from moving downward because, in such action, the wedge portion 2 of the base member will effect repression or outward movement of the locking pin.

The clamp mechanism for securing the two members in fixed relationship is constructed as follows: 8 indicates a fitting comprising an upright portion conforming internally to the contour of member 1 and snugly fitting the same, and a top portion or arm 9 projecting beyond the opposite side of the last-named member and conforming internally to and snugly fitting the opposite side of the latter from the upright portion 8, the circular opening thus provided by the two portions of the fitting being diametrically enlarged to provide a socket 10 receiving the lower end of the upper member 4, and to secure the fitting and the last-named member permanently together, the lower end of the latter is welded to the fitting in said socket or otherwise firmly secured thereto so that upward or downward movement of either is participated in by the other. The free or outer end of the arm 9 is bifurcated as at 11 for a purpose which hereinafter appears, and near the inner end of the bifurcation the arm is provided with a depending perforated lug 12. The lower portion of the fitting is enlarged so as to afford a relatively wide downwardly-facing bottom 13 against which a lifting jack, not shown, or its equivalent, may be applied for effecting upward movement of the upper member when the resistance to such movement is too great to be overcome by manual power. The fitting is also provided with a groove 14 extending transversely with respect to the arm 9, and centrally of said groove the underlying por-

tion is provided with a recess 15 to accommodate downward movement of the handle 16 of a loop-shaped lever. The lever consists of a pair of side portions 17 connected at the handle end by a cylindrical pivot portion 18 engaging the groove 14, and at the other end by a cross piece 19 paralleling the pivot portion 18, the cross piece 19 being preferably elongated vertically and projecting to a higher plane than the pivot portion for facilitating the clamping operation.

A jaw 20 stands in parallel relation to the fitting 8 at the opposite side of the base member and some distance below the arm 9, said jaw conforming internally to the contour of the base member and having teeth 21 for more effective gripping engagement with said base member. The jaw is also provided with a transverse groove 22 paralleling groove 14 and receiving the outer portion 19 of the loop-shaped lever. At its upper end the jaw is provided with an upstanding perforated lug 23 connected with lug 12 by a retractile spring 24 having a tendency to pull upward on the jaw and thereby rock the lever and cause it to effect clamping action of the fitting and jaw on member 1. The jaw is provided with an upstanding bolt 25 which projects through the bifurcation 11 of arm 9 and is engaged by a hand wheel 26. The hand wheel has a depending hub portion 27 extending through the bifurcation 11 and provided with a flange 28 at its lower end, the arrangement being such that when the hand wheel is turned sufficiently in one direction it will bear down on the arm 9 and tend to raise the jaw and thereby through the rocking of the lever, intensify the clamping action of the jaw and fitting on member 1. Reverse movement of said hand wheel brings the flange 28 against the under side of arm 9 and therefore tends to effect downward pressure on the jaw and relax the clamping action of the fitting and jaw on member 1. In this connection it should be stated that these operations can be performed effectively as explained only when the shore is lightly loaded. When carrying a heavy load it is impracticable to turn the wheel by hand for release purposes after the flange 28 abuts arm 9, and the release in such case is effected by striking downward upon the upper end of the jaw with a hammer, it being understood that the fitting and jaw will be made of metal to withstand such treatment.

Assuming that the parts are in operative position with the fitting and jaw clamped firmly against the lower member and the upper member adjusted upward nearly to its limit, as shown, it will be noted that the hub flange 28 is away from the lower side of the arm 9. If there is no heavy load on the shore, the operator can grasp and turn the wheel 26 and thus effect downward movement of the jaw so that the upper member together with

the fitting and jaw may slide downward on the base member, this movement continuing if desired until the shoulder 3 encounters and is arrested by the stop pin 6. If it is desired to raise the upper member, the operator applies lifting force to the handle 16. This action at first results in cross piece 19 forcing the jaw downwardly and outwardly to withdraw it from clamping engagement with member 1, and then causes the fitting and jaw together with the member 4, to move upward the requisite distance, the swing of the lever around its portion 14 being limited by abutment of the portion 17 with stop 17^a, at which time the loop-shaped lever is in horizontal position, the release of the handle resulting in the automatic reclamping action of the fitting and jaw.

If a load is imposed on the shore and it is desired to lift said load, force is applied upwardly on the fitting by means of a jack or other power appliance, and upon the removal of such force the fitting and jaw automatically hold the members in fixed relationship. The hand wheel 26 will now be screwed down tight as shown in the drawing to increase the clamping pressure and at the same time to supply slack or space between flange 28 and the lower face of arm 9 to accommodate settling should the load increase.

From the above description it will be apparent that I have produced a shore which embodies the features of advantage set forth as desirable in the statement of the objects of the invention, and which may be modified in minor particulars without departing from the principle of construction and mode of operation involved, or from the spirit and scope of the appended claims.

I claim:

1. In a shore, a fixed lower member, an upper member fitting telescopically on the lower member, a depending extension for the upper member fitting at its upper end entirely around the lower member and at its lower end partly around the lower member, and provided in its lower portion with a pivot groove; said extension having an outwardly projecting arm at its upper end at the opposite side of the lower member from said groove, a jaw underlying said arm and disposed adjacent the lower member at the diametrically opposite side thereof from said groove and provided with a threaded arm extending up through said arm of the said extension, a nut bearing upon said extension and rotatable relative thereto and engaging said threaded arm, and a lever pivoted in the pivot groove and fitting around the lower member and engaging the said jaw for clamping the latter against the lower member.

2. In a shore, a fixed lower member, an upper member fitting telescopically on the lower member, a depending extension for the upper member fitting at its upper end entirely

around the lower member and at its lower end partly around the lower member, said extension having an outwardly projecting arm at its upper end at the opposite side of the 5 lower member from said groove, a jaw underlying said arm and disposed adjacent the lower member at the diametrically opposite side thereof from said groove and provided with a threaded arm extending up through 10 said arm of the said extension, a nut bearing upon said extension and rotatable relative thereto and engaging said threaded arm; a retractile spring between and connecting the arm of said extension and the underlying jaw, 15 and a lever pivoted to the said extension and fitting around the lower member and adapted for clamping the jaw against the lower member.

3. In a shore, a pair of telescopic members, the external member being cut away throughout a part of its length to expose the inner member and being provided with a stop shoulder, a yoke member pivotally mounted on the external member and having 25 a cam portion on the opposite side of the shore and spaced from the exposed portion of the inner member, said yoke being limited in its movement in one direction through con-

tact with said stop shoulder, and a jaw interposed between said cam portion of the yoke and the inner member, and a stem extending from said jaw and adjustably secured to the yoke member. 70

4. In a shore, a pair of telescopic members, the external member being cut away through a part of its length to expose the inner member, a yoke pivotally mounted on the external member and enclosing the inner member and provided with an operating handle, a jaw vertically adjustable relative to the outer member and engaging the inner member within the yoke and at the opposite side of 75 said member from the yoke handle, the jaw having parts overlying and underlying the yoke to insure movement of the jaw responsive to pivotal action of the yoke upwardly or downwardly, and means connected to the jaw and operable to apply pressure upwardly or downwardly on the outer member to intensify or relax the clamping pressure of the jaw on the inner member applied by the load of the outer member through the pivoted yoke. 80 85 90

In testimony whereof I affix my signature.

EARL C. CHILDERS.
